Arthur Webb Parsons
BY Phillips Abbott
his. ATTORNEY

UNITED STATES PATENT OFFICE.

ARTHUR W. PARSONS, OF BROOKLYN, NEW YORK.

COCK.

SPECIFICATION forming part of Letters Patent No. 275,406, dated April 10, 1883.

Application filed November 23, 1882. (No model.)

To all whom it may concern:

Be it known that I, ARTHUR WEBB PARSONS, of the city of Brooklyn, county of Kings, and State of New York, have invented a new and useful Improvement in Cocks, of which the following is a full, clear, and exact description, reference being had to the accompanying drawings, in which like letters indicate like parts.

10 My improved cock is peculiarly adapted to be used in connection with filtering apparatus, although it may be used with any other apparatus or system of piping, if desired.

The peculiar feature of the cock consists in 15 so constructing its barrel and plug that the plug shall have but two passages through it, which shall connect with suitably-located ports through the barrel to which the piping shall be connected, whereby what may be called 20 "direct," "reverse," and "by-passing" flows of liquid may be obtained; and the best method known to me of constructing it is to have the centers of the two passages in the plug and the centers of all the ports in the barrel 25 on the same transverse plane.

I do not claim, broadly, a single cock so constructed that by rotating its plug liquid may be made to flow through such apparatus as may be connected with it in opposite directions, and also by-passed, cutting out such apparatus, for I am aware that such a cock has 30 been constructed.

In the drawings I have shown the cock constructed with the ports and plug-passages all 35 on the same plane, and have represented it as connected with an ordinary filtering apparatus. The ports in the barrel of the cock, however, need not necessarily be on the same transverse plane. They may be in different 40 planes, the passage or passages through the plug curving to connect with them.

Figure 1 illustrates a section of the cock through the center of the passages in the plug and of the ports in the barrel and connected 45 with a filter not in section. The cock-plug is in the proper position to filter the water. Fig. 2 illustrates the cock in the same section and with the plug in position to effect a reverse flow of liquid to cleanse the filter. Fig. 3 illustrates the cock in the same section and with the plug in position to by-pass the liquid.

Fig. 4 illustrates a top view of the cock, showing the handle and stops to regulate the turning of the plug.

In the drawings, X is the filter. X' and X² are two ordinary screw-couplings, whereby the filter may be readily disconnected from the piping and removed.

A is the barrel of the cock, furnished with five ports, H, S, D, F, and F'. They are distant from each other from center to center on the inside of the barrel exactly one-fifth the circumference of the barrel on the inside. The port H connects with the house-pipe, S connects with the supply-pipe, D connects with 60 the drain-pipe, F connects with one end of the filter, and F' with the other end.

C is the plug of the cock. C' and C² are the two passages through it. These passages are so distanced that C' connects with any two of 70 the ports which are adjacent to each other, and C² connects with any two ports which are separated by one interposed port; and to secure this the centers of the ports on the inside of the barrel should be, as already stated, substantially one-fifth the circumference of the 75 cock on the inside of the barrel apart. C' extends to the periphery of the plug, although it is not necessary that it should do so. C² passes through the plug, leaving the bearing-surface C³ outside of it. By reference to the drawings it will be at once seen that when the plug is turned into the several positions illustrated the liquid brought to the cock by the supply-pipe S will be made to flow in different 80 directions, as I have indicated by arrows on the drawings—that is to say, in Fig. 1 the water is passing from the supply-pipe through the plug-passage C² to the filter, through it and the plug-passage C' to the house-pipe. When 85 desired to cleanse the filter, the plug is turned to the position shown in Fig. 2. Now, the water passes from the supply-pipe through C², through the filter in the opposite direction, and thence through C' to the drain-pipe, cleansing 90 the filter; and when the plug is turned as shown in Fig. 3 the water is received from the supply-pipe and passes through C' direct to the house-pipe, and the filter is cut out.

In Fig. 4, I show the handle of the plug at 100 B and stops I I located on the top of the barrel of the cock, against which the handle shall

strike, thus determining the degree of rotation to be given to the plug.

Having thus described my invention, I claim—

- 5 1. As a new article of manufacture, a cock having five ports and two passages only through its plug, the said ports and the said passages being all on the same transverse plane, substantially as and for the purposes set forth.
- 10 2. As a new article of manufacture, a cock

having five ports in its barrel and two passages only through its plug, one passage connecting with adjacent ports and the other passage connecting with alternate ports, substantially as and for the purposes set forth.

ARTHUR WEBB PARSONS.
